B. W. Avery INVENTOR
BY *Victor J. Evans*

INVENTOR

ATTORNEY

UNITED STATES PATENT OFFICE.

BRUCE W. AVEY, OF WHITING, INDIANA.

EXHAUST-GAS CONVEYER.

1,390,950.

Specification of Letters Patent. Patented Sept. 13, 1921.

Application filed March 15, 1920. Serial No. 365,888.

To all whom it may concern:

Be it known that I, BRUCE W. AVERY, a citizen of the United States, residing at Whiting, in the county of Lake and State 5 of Indiana, have invented new and useful Improvements in Exhaust-Gas Conveyers, of which the following is a specification.

This invention relates to means for conducting the exhaust gases of automobiles, 10 motors, stationary engines and the like to the exterior of garages or other buildings so that said gases will not remain in the building and thus asphyxiate or injure the health of the occupant.

15 The principal object of the invention is to provide a flexible tube or other hollow conveyer, connected with a pipe which passes through a wall of the building, and having means whereby it may be easily and quickly 20 attached to the outlet end of the muffler of the engine.

Another object of the invention is to provide means for holding the pipe or pipes out of the way when not in use.

25 This invention also consists in certain other features of construction and in the combination and arrangement of the several parts, to be hereinafter fully described, illustrated in the accompanying drawings and 30 specifically pointed out in the appended claims.

In describing my invention in detail, reference will be had to the accompanying drawings wherein like characters denote like 35 or corresponding parts throughout the several views, and in which:—

Figure 1 is a sectional view through a portion of the garage showing the simplest form of the invention.

40 Fig. 2 is a like view showing the invention in use in a large garage.

Fig. 3 is a detail sectional view of Fig. 2.

Fig. 4 is a sectional detail view showing the means for connecting the flexible tube with 45 the outlet of the exhaust.

Fig. 1 shows the invention in use on a private garage for holding a single car.

In this view a pipe 1 is passed through 50 a wall 2 of the garage so that its end projects from the exterior of the wall. The inner end of this pipe has a flexible tube 3 connected therewith and this tube is long enough to extend to the outlet 4 of the muffler 5 of the automobile. The end of 55 the tube is connected with said outlet by a set screw 6 or the like.

It will thus be seen that when the engine of the car is running the exhaust gases will be carried to the exterior of the garage so that a person may tune up the engine or 60 test the same with the garage doors shut and not be in danger of being injured by the exhaust gases.

Fig. 2 shows the invention applied to a large garage. In this form of the invention 65 a main pipe 7 is located in the building with one end leading to the exterior thereof. Couplings 8 are located in said pipe and these couplings receive the ends of the flexible tubes 9. These tubes are each provided 70 with the set screw 6' by which the tube may be connected with the muffler of the car.

I also provide means for holding the tubes in raised position so that they will be out of the way when not in use. Such means 75 may consist of a cable 10 having a hook at one end for engaging each tube and a weight 11 at its other end, said cable passing over a pulley 12. In this way when it is desired to start the motor of the car the 80 attendant would first take hold of the end of the tube pulling the same down against the action of the weight and connecting it with the muffler. In this way the gases will pass through the tube into the pipe 7 and 85 from this pipe to the exterior of the building. Check valves may be placed in the tubes to prevent the gases from flowing back when the tube is not in use.

It is thought from the foregoing description 90 that the advantages and novel features of my invention will be readily apparent.

I desire it to be understood that I may make changes in the construction and in the combination and arrangement of the several parts, provided that such changes fall 95 within the scope of the appended claim.

What I claim is:—

Conveyer means for the exhaust gases of 100 automobiles in garages comprising a main pipe leading to the exterior of the building, a number of flexible pipes connected with the main pipe, means for connecting the inner ends of said flexible pipes to the outlet end of the muffler and weighted means for 105 normally holding the flexible pipes in raised position when not in use.

In testimony whereof I affix my signature.

BRUCE W. AVERY.
